UNITED STATES PATENT OFFICE

158,298

FAUCET ATTACHMENT

Carl E. Lehman, Evanston, Ill.

Application December 29, 1948, Serial No. 150,435

Term of patent 14 years

(Cl. D91—3)

To all whom it may concern:

Be it known that I, Carl E. Lehman, a citizen of the United States, residing at Evanston, in the county of Cook and State of Illinois, have invented a new, original, and ornamental Design for a Faucet Attachment, of which the following is a specification, reference being had to the accompanying drawings, forming a part thereof.

In the drawings,

Figure 1 is a side elevational view of a faucet attachment showing my new design;

Fig. 2 shows a top plan view of the device illustrated in Fig. 1; and

Fig. 3 shows a bottom plan view of the device illustrated in Figs. 1 and 2.

I claim:

The ornamental design for a faucet attachment, as shown.

CARL E. LEHMAN.
